ADJUSTABLE DOOR HOOK

Nordell N. Huffaker, 655 Galisteo St.,
Santa Fe, N. Mex.

Filed Oct. 17, 1962, Ser. No. 72,157

Term of patent 14 years

(Cl. D10—7)

FIG.1

FIG.4

FIG. 1 is a perspective view of the adjustable door hook, showing my new design;

FIG. 2 is a side elevational view;

FIG. 3 is an exploded view; and

FIG. 4 is an end elevational view with portions omitted for convenience of illustration.

I claim:

The ornamental design for an adjustable door hook, as shown and described.
